AUXILIARY RACK FOR USE WITH DISPLAY RACKS

Willard H. Kallhorn, Kansas City, Mo., assignor to Hallmark Cards, Incorporated, Kansas City, Mo., a corporation of Missouri

Application June 21, 1954, Serial No. 438,080

5 Claims. (Cl. 211—50)

This invention relates to an auxiliary rack adapted for use in connection with display racks of the type described in United States Letters Patent No. 2,067,051, for merchandizing greeting cards and similar articles that are best displayed with the face side presented at right angles to the normal lines of vision of the viewer.

However, when thus displayed, all of the various cards have substantially the same relative prominence in the display and consequently it is difficult to highlight any one card. This is also true in more or less degree with other types of racks.

Therefore, the principal object of the present invention is to provide a relatively simple auxiliary rack that is adapted for attachment to a primary rack for highlighting certain cards or articles of merchandise.

Other objects of the invention are to provide an auxiliary rack that is adapted for support between the sides of adjacent display racks, thereby utilizing space that has not been used; to provide an auxiliary rack that does not objectionably conceal or interfere with display of adjacent cards in the primary racks; to provide an auxiliary rack having supports for presenting the cards therein at right angles to the lines of vision in the same manner as the support of the cards in the primary rack; to provide an auxiliary rack having card supports that project the cards outwardly and forwardly from the main display; and to provide an auxiliary rack with attaching means for engaging parts of the primary rack so as to automatically present the cards in the desired position.

In accomplishing these and other objects of the invention, hereinafter pointed out, I have provided improved structure the preferred forms of which are illustrated in the accompanying drawings wherein:

Fig. 1 is a perspective view of an auxiliary rack constructed in accordance with the present invention and showing support thereof by adjacent primary racks.

Fig. 2 is a rear view of the auxiliary rack with parts of the primary racks broken away to better illustrate the construction and support of the auxiliary rack.

Fig. 3 is a vertical cross section through a portion of one of the primary racks showing the support of the auxiliary rack.

Referring more in detail to the drawings and first to the form of auxiliary rack shown in Figs. 1 to 3 inclusive:

1 designates an auxiliary rack constructed in accordance with the invention and which includes a bracket 2 which may be formed of a flat sheet metal stamping or of a wire bent to shape to provide a shank 3 having forwardly extending arms 4 and 5 terminating in lateral flanges 6 and 7 for attaching holders or receptacles 8 and 9 as later described. The shank portion 3 of the bracket 2 is joined with the arms 4 and 5 on rounding curves 10 and 11. Formed in opposite side edges of the shank are notches 12 and 13 to accommodate fastening devices such as screws (not shown) in case the bracket is to be attached to the side of an end-most primary rack. Extending laterally from the arms 4 and 5 are lugs 14 and

2

15 adapted to seat on the front edges of the primary rack as later described. The upper lug 15 terminates in a rearwardly extending hook 16 that is adapted to engage over a front rail of one of the primary racks to support the auxiliary rack vertically between the primary racks while the lugs 14 and 15 support the bracket with the holders 8 and 9 in spaced relation with the fronts of the primary racks.

The holders 8 and 9 in this form of the invention are formed of sheet metal and each has a generally rectangular back or easel portion 17 having a rounding upper edge 18 and a shelf 19 extending forwardly from the lower edge to terminate in an upwardly extending front rail 20, for forming a pocket. The rail 20 cooperates with the back 17 and shelf 19 to seat the lower marginal portion of a pack of cards or similar merchandise as later described. The back 17, shelf 19 and the front rail 3 may be formed of a single sheet of metal bent transversely on lines of fold 21 and 22.

20 Fixed to the front of the rail is a label or name plate 23 which may bear any suitable material pertaining to the cards on display. The labels may be fixed to the front of the rail in any suitable manner but in the illustrated instance, the labels are formed of sheet material 25 shaped to conform with the rail and are secured thereto by fastening devices such as rivets 24.

In order to support the cards in a sidewise direction, and prevent any lateral disarrangement, the back rest 17 is preferably provided with forwardly extending fingers 30 25 and 26 which are of like construction in that they include shanks 27 and 28 extending laterally from the ears through an upper and lower series of loops 29 and 30 that are stamped from the metal of the back rest as best shown in Fig. 2.

35 The sets of loops 29 and 30 are offset with respect to each other in order that the shanks may be of a length to give a maximum spacing of the fingers 25 and 26 and to prevent interference when the shanks slide past each other in accommodating the ears to relatively narrow cards. 40 The fingers, however, are in the same relative position horizontally since the shanks are attached near one edge of the ears. Then when the shanks are inserted in the loops they are reversed with respect to each other to bring the ears in horizontal alignment.

45 While the auxiliary rack may be used on various primary racks it is especially useful in connection with racks of the type disclosed in the above mentioned patent, however, they will be briefly described as follows in order to give a better understanding of the manner in which 50 the auxiliary racks are used.

Each rack includes side walls 31 and 32 having a generally upwardly and rearwardly sloping front edge 33, following the eye vision contour of the racks and having substantially flat outer faces 34 whereby the end of one 55 rack may abut the end of another rack as shown in Fig. 3, the side walls of the racks carry therebetween a plurality of transverse back rests 35 and shelf members 36 in the manner of a series of steps as shown in Fig. 3, and which form supports for cards on display. The cards are retained by front rails 37.

60 In mounting the auxiliary racks, the primary racks are moved apart a sufficient distance to pass the shanks 3 of the brackets therebetween so that the lugs 14 and 15 seat upon the curved edges 33 of one of the racks as shown in Fig. 2, while the hook 16 engages over the upper edge 65 of one of the front rails 37 to support the rack in desired vertical relation. The cards to be featured are then placed in their respective holders 8 and 9 and the fingers 25 and 26 are adjusted to engage the sides of the cards to hold the pack in orderly condition.

70 From the foregoing it is obvious that I have provided an auxiliary rack for greeting cards and similar merchan-

dise which is of simple and relatively inexpensive construction and which may be used to highlight certain particular merchandise from the merchandise displayed in an eye vision rack.

What I claim and desire to secure by Letters Patent is:

1. An auxiliary rack including a substantially flat shank portion having forwardly extending arms at respective ends of the shank portion, stops extending laterally from said arms, a hook projecting from one of said stops, a holder having a back portion fixed to one of said arms, a shelf portion on the lower edge of the back portion and a front rail portion cooperating with the back portion to form a pocket therebetween, said back portion having guide loops, and side members having shanks slidably engaging in said loops.

2. An auxiliary rack including a substantially flat shank portion having forwardly extending arms at respective ends of the shank portion, stops extending laterally from said arms, a hook projecting from one of said stops, a holder having a back portion fixed to one of said arms, a shelf portion on the lower edge of the back portion and a front rail portion cooperating with the back portion to form a pocket therebetween, one portion of the holder having guide channels, and side members having shanks slidably engaging in said guide channels.

3. An auxiliary rack for support by a primary display rack, including a shank portion having forwardly extending arms at respective ends of said shank portion, stops fixed relative to said arms and extending laterally thereof, means fixed relative to said shank portion for cooperation with the stops in engagement with a primary rack for supporting the auxiliary rack thereon, a holder having a back portion fixed to one of said arms, a shelf portion on the lower edge of the back portion and a front rail portion cooperating with the back portion to form a pocket therebetween, one portion of the holder having guide channels, and side members having shanks slidably engaging in said guide channels.

4. An auxiliary rack supported by a primary display rack having longitudinal display shelves and front rails arranged in rearwardly and upwardly stepped relation and carried by side members, said auxiliary rack including a

shank portion having forwardly extending arms at respective ends of said shank portion, stops fixed relative to said shank portion and extending laterally thereof, a hook fixed relative one of the arms for engaging over a front rail of the primary rack and for cooperation with the engagement of the stops with said primary rack for supporting the auxiliary rack thereon, a holder having a back portion fixed to one of said arms, a shelf portion on the lower edge of the back portion and a front rail portion cooperating with the back portion to form a pocket therebetween, one portion of the holder having guide channels, and side members having shanks slidably engaging in said guide channels.

5. An auxiliary rack supported by a primary display rack having longitudinal display shelves and front rails arranged in rearwardly and upwardly stepped relation and carried by side members, said auxiliary rack including a shank portion having a plurality of forwardly extending arms spaced along said shank portion, stops fixed relative to said shank portion and extending laterally thereof, means fixed relative to said shank portion for cooperation with the stops in engagement with a primary rack for supporting the auxiliary rack thereon, a holder for each arm and having a back portion fixed to the respective arm, a shelf portion on the lower edge of the respective back portion and a front rail portion cooperating with the respective back portion to form a pocket therebetween, one portion of each holder having guide channels, and side members for the respective holders having shanks slidably engaging in said guide channels thereof.
